CHRISTMAS TREE STAND

Samuel Wagner, Sheridan, Wyo., and Theodore K. Kell-
ner, Box 237, 1315 Ellis St., Waukesha, Wis.
Filed Apr. 27, 1953, Ser. No. 351,446
2 Claims. (Cl. 248—45)

This invention relates to a Christmas tree stand and more particularly to a tree-supporting stand which is readily constructed and assembled, durable, easily filled with water and in which the tree may be readily disposed and manipulated.

According to this invention, a tree-supporting stand may include a water-tight container including a frusto-conical shaped funnel-like top having a central opening for reception of the tree trunk. The funnel-like top, of course, aids in filling the container with water for the tree. For support of the tree trunk, a sleeve is preferably fixed within the opening in the top and means such as thumb screws are threaded through the walls of the sleeve. Holes are provided in the top adjacent the sleeve for filling the container with water.

In accordance with a highly important feature of the invention, the bottom of the container has a central cup-shaped recess and a member arranged to be secured to the end of the tree trunk has a rounded surface portion riding in the recess with a minimum of friction. By this feature, the thumb screws, or other trunk-holding means, may be loosened and the tree readily rotated about its axis so as to be easily decorated. The member may be of a plastic material although other materials such as wood and metal are suitable, and it preferably has a screw embedded therein for securing the same to the end of the tree trunk.

In accordance with a specific feature of the invention, the bottom is stamped from sheet metal and has a down-turned annular peripheral flange and a sheet metal ring forms the side of the container and tightly embraces at its lower end of the peripheral flange of the bottom. The lower edges of the ring is folded outwardly and upwardly to form a seam and the lower edge of the peripheral flange of the bottom is folded outwardly and upwardly about said seam so as to form a double seam and provide a strong and durable construction.

In accordance with another specific feature of the invention, the funnel-like top is stamped from sheet metal and has an upturned annular peripheral flange fitted within the annular side wall with the upper edge of the upturned flange being turned inwardly and downwardly and with the upper edge of the annular side wall being turned inwardly and downwardly thereabout so as to form a double seam which is very strong and durable.

An object of this invention, accordingly, is to provide an improved tree-supporting stand which is readily constructed and assembled and yet is strong and durable.

Another object of this invention is to provide an improved tree-supporting stand including a water-tight container and a funnel-like top by which the container may be readily filled with water for feeding the tree trunk.

A further object of this invention is to provide an improved tree-supporting stand in which a tree may be readily disposed, manipulated and secured.

Still another object of this invention is to provide an attachment for the base of a tree by which it is rendered readily rotatable within a supporting stand.

This invention contemplates other objects, features and advantages which will become more fully apparent from the following detailed description taken in conjunction with the accompanying drawing which illustrates a preferred embodiment and in which:

FIGURE 1 is a top plan view of a tree-supporting stand embodying the principles of the present invention;

2

FIGURE 2 is a sectional view through the stand of FIGURE 1 taken substantially along lines II—II; and

FIGURE 3 is an enlarged detail view of the attachment constituting an important feature of this invention.

Referring to the drawing, reference numeral 10 generally designates a tree-supporting stand embodying the principles of this invention. The stand 10 is in the form of a water-tight container which may be of a stamped sheet metal construction, although other forms of construction are suitable. In accordance with an important feature of the invention, the stand 10 has a frusto-conically shaped funnel-like top 11 which has a central opening for reception of a tree trunk 12. To hold the tree trunk 12 in position, a sleeve 13 is fixed within the central opening in the top 11, a down-turned annular flange 14 about the opening being tightly engaged with the lower end of the sleeve 13. A plurality of thumb screws 15 are threaded through the wall of the sleeve 13 to engage the tree trunk 12, plates 16 being disposed at the ends of the thumb screws 15 to prevent the screws from becoming embedded in the tree trunk 12.

At least one and preferably a plurality of holes 17 are provided in the top 11 adjacent the sleeve 13. To fill the stand 10 with water for absorption by the tree trunk, the water is merely poured into the funnel-like top 11 and it will drain through the holes 17 into the space about the lower end of the tree trunk 12. It will be apparent that the large area and funnel-like form of the top 11 makes it easy to fill the stand with water without spilling any water.

The stand 10 has a bottom 18 which may preferably be stamped from sheet metal and has a central cup-like recess 19 in alignment with the sleeve 13. A side wall 20 may be of annular form and defined by a ring of sheet metal. For rigidity and for ornamental appearance, the side wall ring 20 may have a plurality of circumferentially spaced vertical rib-like projections 21 as illustration in FIGURE 1.

A specific feature of the invention is in the manner in which the bottom 18 is secured to the annular side wall 20. According to this feature, the bottom 18 has a down-turned annular peripheral flange 22 which is tightly embraced by the lower end of the annular side wall 20. The lower edge of the side wall 20 is folded outwardly and upwardly to define a first seam 23 and the lower edge of the annular flange 22 is folded outwardly and upwardly at 24 about the first seam 23 to thereby define a double seam and provide a rigid, durable water-tight junction as well as a rounded edge for engaging the supporting surface for the stand.

Another specific feature of the invention is in the manner in which the top 11 is secured to the annular side wall 20. The top 11 has an up-turned annular peripheral flange 25 which is tightly embraced by the upper end portion of the annular side wall 20 and has an upper edge turned or folded inwardly and downwardly to define a first seam with the upper edge of the annular side wall 20 being turned inwardly and downwardly at 26 about said first seam to thereby define a double seam and provide a secure interengagement between the top 11 and the annular side wall 20 with no objectionable sharp edges.

A further and highly important feature of the invention is in an attachment 27 for supporting the lower terminal end of the tree trunk 12 in the recess 19 in the bottom 18. This attachment 27 is rounded surface portions for engaging within the recess 19 with a minimum of friction so that the tree may be readily rotated for ease in decorating the same and to obtain the optimum positioning thereof. The attachment may be preferably of a plastic material although wood, metal or other materials are, of course, satisfactory. For economy of material, the attachment may preferably take the form illustrated in

which it includes a central body portion 27a and a plurality of circumferentially spaced radially extending ribs 27b. As noted above, the surfaces of the attachment 27 are rounded for riding in the recess 19 with a minimum of friction and they may preferably be of segmental spherical form.

To secure the attachment 27 to the lower terminal end of the tree trunk 12, a screw 28 is embedded therein and arranged to be threaded into the end portion of the tree trunk 12.

It will be understood that modifications and variations may be effected without departing from the spirit and scope of the novel concepts of the present invention.

We claim as our invention:

1. A tree-supporting stand, comprising:

- (1) a bottom having a central cup-shaped recess, means rigidly connected to said bottom and including
  - (a) a member substantially above said recess defining an opening coaxial with said recess and adapted to have a tree trunk passed therethrough in radially spaced relation,
  - (b) said member carrying a circumferentially spaced plurality of tree trunk retaining screws threadedly operable on radial axes and having plate elements on their trunk-engaging ends to engage the tree trunk and prevent embedding of the screw ends in the tree trunk but arranged for engaging and loosely holding at times the tree trunk in alignment with said recess,
  - (2) and a member arranged to be secured to the end

of a tree trunk and having segmental spherical surface portions in the form of circumferentially spaced radially and upwardly extending ribs for riding in said recess with a minimum of friction,

5 whereby the tree can be rotated in the stand.

2. A tree-supporting stand, comprising:

- (1) a bottom having a central cup-shaped recess, means secured to said bottom for engaging and holding a tree trunk in alignment with said recess,
- (2) and a member arranged to be secured to the end of a tree trunk and having segmental spherical surface portions in the form of circumferentially spaced radially and upwardly extending ribs for riding in said recess with a minimum of friction,
